SHELL CHARGER

Willard F. Thoma, Detroit, Mich., assignor to National Stamping Company, Detroit, Mich., a corporation of Michigan

Application July 19, 1941, Serial No. 403,189

1 Claim. (Cl. 89—34)

This invention relates to shell chargers, that is, devices of the type adapted to secure a plurality of shells together for loading purposes in rapid fire guns and cannon, the principal object of the invention being the provision of such a charger that is simple in construction, efficient in operation, and economical to manufacture.

Objects of the invention include the provision of a shell charger formed from sheet metal; the provision of a charger of the type described that is formed from relatively thin sheet metal and is, therefore, light in weight; the provision of a shell charger that is formed from light sheet metal and so constructed and arranged as to embody a maximum amount of strength for its weight; the provision of a shell charger substantially eliminating the need of machining operations thereon during its manufacture; and the provision of a shell charger of the general type above described formed from relatively thin sheet metal and including certain novel details of construction particularly adapting it to the work to be performed thereby.

The above being among the objects of the present invention the same consist in certain novel features of construction and combinations of parts hereinafter described with reference to the accompanying drawing, and then claimed, having the above as well as other objects in view.

In the accompanying drawing which illustrates suitable embodiments of the present invention and in which like numerals refer to like parts in the several different views,

Figure 1 is a plan view illustrating four shells operatively connected together by a loading device or charger constructed in accordance with the present invention;

Fig. 2 is an enlarged plan view of the charger shown in Fig. 1;

Fig. 3 is a rear elevational view of the charger shown in Fig. 2 and taken as looking on the line 3—3 of Fig. 2;

Fig. 4 is a front elevational view of the charger shown in the preceding views and taken as looking on the line 4—4 of Fig. 2;

Fig. 5 is a transverse sectional view of the charger taken on the line 5—5 of Fig. 3;

Fig. 6 is a transverse sectional view taken on the line 6—6 of Fig. 3;

Fig. 7 is a fragmentary, vertical sectional view taken on the line 7—7 of Fig. 2 to better illustrate the form of connection between the two main elements of the charger at the ends thereof;

Fig. 8 is a fragmentary, plan view of a slightly modified form of charger;

Fig. 9 is a fragmentary, rear elevational view, taken as on the line 9—9 of Fig. 8, to better illustrate the construction shown in Fig. 8; and

Fig. 10 is a view similar to Fig. 8, but illustrating a still further modified form of construction.

Shell chargers of the type herein under consideration are employed for removably securing a plurality of shells together so as to facilitate the loading or charging of the same in a rapid fire gun or cannon. While they may, of course, be adapted for any size of shells, it may be noted that the particular type shown has particularly been adapted for thus removably securing together shells of the 40 mm. type.

These charges comprise a rigid device having partially cylindrical pockets therein adapted to receive the butt end of the shell and include a portion adapted to fit within the usual peripheral groove at the base of such shell so as to locate the shells axially of the device. Additionally, they include a spring pressed plunger movable in a direction axially of the shell and including a part adapted to be removably received in the annular groove in the base of the shell to thereby complete the removable locking of the shell to the device. Inasmuch as such shells taper in diameter from the base toward the tip, the chargers are usually arranged so as to maintain the sides of the shells in approximate parallelism with each other, thus necessitating the charger to be generally curved in plan view.

In the past, it has been conventional practice to form such shell chargers from aluminum castings with only the plungers and their cooperating springs and clips being separately formed and later applied thereto. When formed from aluminum castings, it is usually necessary to perform some machining operations on the body of the chargers. At the present time, there is a scarcity of aluminum available for military activities and it is, therefore, desirable to eliminate the use of such metal wherever possible if this can be done without disadvantage. The present invention has been developed as the result of the scarcity of aluminum and although it may be formed from sheet aluminum or any other suitable sheet metal, is preferably formed from sheet steel. It has been found that by the practices of the present invention a shell charger is provided that when formed of steel is of substantially no greater weight than those of an equivalent size formerly formed from aluminum,

is materially cheaper to build, is of equal if not greater strength than the conventional aluminum type, and may be accurately constructed without any machining operations whatever except upon the plungers thereof.

Referring now to the accompanying drawing, and particularly to Fig. 1, it will be noted that there are illustrated four shells, each comprising a casing 11 carrying a projectile 12, the latter being provided with the usual gas ring 14. As is conventional, the shell cases 11 are each provided with a peripheral groove 16 adjacent the base thereof and, as best brought out in Fig. 5, the base ends of the cases 11 are each provided with an annular groove 18 in relatively closely spaced relation with respect to the outer margin of the base.

Generally speaking, these chargers are of rigid construction formed to provide a plurality of partially cylindrical seating surfaces arranged in transversely spaced relation for reception of the base end of the shell, a partially circular ridge or bead adapted to be received in the groove 16 of the corresponding shell case and an axially movable spring pressed plunger having a clip fixed thereto adapted to be removably received in the corresponding groove 18 of the cooperating shell, to thereby releasably lock the shells in position on the charger.

In the present case, the body of the charger is made up of two main parts, namely, the parts indicated generally at 20 and 22. The part 20 is formed from relatively thin sheet metal, as for example No. 18 gauge steel for a charger for 40 mm. shells, and is of generally L-shape in cross section, including a flat base 24 and an upstanding integral wall portion 26 arranged generally in perpendicular relationship with respect to the base 24. The upper edge of the side wall portion 26 is formed or scalloped to provide four partially cylindrical or arcuate surfaces or seats 28 of a diameter to substantially closely fit that portion of the various cases 11 adapted to be received therein. The metal along the upper margin of the side wall 26 is rearwardly flanged or turned as at 30 in perpendicular relationship with respect to the plane of the side walls 26, not only to strengthen the structure, but to provide a relatively wide surface for the seats 28 for engagement of and support of the shell cases 11 thereon. The flange 30 is continuous from one end of the member 20 to the other so as to enhance the rigidity of the structure.

The member 22 is also generally of L-section and includes a flat but narrower base 34 and an upstanding wall 36 integral therewith and arranged in perpendicular relationship with respect to the plane of the base 34. Like the member 20, its upper edge is scalloped and forwardly flanged to provide four partially circular scallops or arcuate portions 38 of a size such as to substantially fit the bottom of the groove 16 in the shell head and each forming a seat for a shell case at the bottom of the groove 16 thereof. The amount which the margins of the side walls 36 are preferably forwardly turned or flanged is such as to provide a shoulder of slightly less width than the width of the groove 16 of the shell cases 11 for reception therein and to aid in the support of the shells thereon. The forward flanging of the upper margin of the wall 36 preferably occurs over the full length of the wall 36 to enhance the strength thereof.

The two members 20 and 22 are arranged with

the member 22 resting upon the member 20 and with the rear edges of the bases 24 and 34 in aligned relation to each other and with the arcuate seat portion 28 concentric with the arcuate seat portions 38 and the bases 24 and 34 are secured together, as by spot welding or the like, in such position. As will be apparent from an inspection of Figs. 2, 5, and 6, the seats 28 and 38 are thus materially spaced from one another and are adapted to engage a shell case 11, as illustrated in Fig. 5.

In order to strengthen the connection between the members 20 and 22, between each adjacent pair of cooperating seats 28 and 38 a post 40, best shown in Fig. 6, is extended and securely staked to each thereof. The posts 40 are of greater vertical dimension than transverse dimension and cooperate with the vertical walls 26 and 36, respectively, to prevent springing of one with respect to the other. Additionally, the side walls 26 and 36 at opposite ends thereof are respectively provided with oppositely disposed flanges or tongues 42 and 44, respectively, arranged in overlapping relation and suitably secured together as by spot welding or the like. Because of the fact that the flanged upper margin of the wall 36 of the member 22 is relatively narrow, it is preferable, in order to further stiffen such wall, to form depressions such as 45 of material area therein at spaced points as indicated.

As mentioned in connection with the description of Fig. 1, the charger in plan view is somewhat arcuate in shape, but is not on a true arc inasmuch as particularly the shoulders on seats 38 in fitting within the grooves 16 of the shell cases 11 must be substantially in the same plane as such grooves. Accordingly, in order to obtain the arcuate effect, the members 20 and 22 are bent substantially on the median lines between the seats 28 and 38, respectively, as clearly brought out in Fig. 2. The member 20, having the relatively wide base 24, is preferably formed of this shape in the stamping operation, but the member 22 having the relatively narrow base 34, may have such base notched out as at 46 at the various points of bend under which conditions it may be formed straight and then bent in the plane of the base 34 to bring it to its required shape before securing it to the member 20.

It will also be noted that the base 34 of the member 22 is provided with an upwardly offset portion 48 having a flat upper surface in vertical alignment with the axis of each of the shell receiving seats of the charger. These upwardly offset portions 48 form abutments for cooperation with the clip which will now be described.

In vertical alignment with each shell case 11 received by the charger, the walls 26 and 36 slidably receive between them a plunger 50. Each plunger 50 has an enlarged head 52 and a reduced end portion 54. For the purpose of receiving the plunger 50, the walls 26 and 36 are provided with openings for receiving the head 52 and the body 50 of the plunger, respectively, the metal of the walls about the margins of such openings being inwardly turned as at 56 and 58, respectively, to provide axially extended bearing surfaces for the plunger. The reduced end portion 54 of each plunger 50 projects rearwardly beyond the rear wall 36 and has rigidly fixed thereto a catch or clip member 60. The catch or clip members 60 are each provided with a flat lower face 62, best brought out in Fig. 3, which lies in normally spaced but relatively close relation with respect to the upper surface of the cooperating

abutment 48, so as to prevent relative rotation of the catch member 60 about the axis of the corresponding plunger 50 without interfering with the movement thereof axially of the corresponding plunger 50. The upper end of the catch member 60 is provided with a forwardly extending end or projection 64 positioned to engage the annular groove 18 in the base of the corresponding shell case 11 when the seat 38 is engaged within the groove 16 of the shell case. The plungers 50 are constantly urged in a forwardly direction by means of a coil spring 66 encircling each plunger 50 and maintained under axial compression between the head 52 of the plunger and the wall 36 of the member 22, the springs 66 thus constantly urging the projection 64 into operative relationship with respect to the groove 18 and the corresponding shell case 10. Thus, from an inspection of Fig. 5, it will be appreciated that engagement of the seat 38 in the groove 16 of the various shell cases 11 holds the shell cases 11 against axial movement with respect to the charger and the inter-engagement of the projection 64 of the member 60 with the grooves 18 in the bases of the shell cases 11 releasably maintains these shells in position in the charger. Obviously, by simply moving the plungers 50 axially against the force of the corresponding spring 66, the projections 54 are withdrawn from engagement with the grooves 18 of the corresponding shell cases, which thereby releases the shell cases for removal from the charger.

It will be appreciated from the foregoing description that the chargers thus provided may be formed from any suitable sheet metal, but from the standpoint of strength and economy of production are preferably formed from steel and suitably treated against corrosion. Being of relatively thin sheet metal, they are relatively light in weight and economical to produce, and the flanges and reinforcements provide the structure with ample strength in spite of the light metal employed in its production.

The metal from which the member 22 is formed is, of course, of considerably less thickness than the width of the groove 16 in the shell cases 10. At the same time, the upper edge of the wall 36 of the member 22 must be of sufficient dimension in the direction of the axis of the shell cases to relatively closely but be slidably received in the groove 16. When it is not desired to flange the

upper edge of the wall 36 to fit the groove 16, as previously described, then resort may be had to the construction illustrated in Figs. 8 and 9, whereby the required thickness of the upper edge of the wall 36 is obtained without the necessity of flanging.

Referring now to Figs. 8 and 9, it will be noted that the construction there shown is identical to that first described with the exception that the wall equivalent to the wall 36, and here indicated at 36', instead of being forwardly flanged is indented at intervals, as at 70, so that, as viewed in Fig. 8, the effective thickness of the upper edge of the wall 36' is equivalent to the thickness of the flanged upper edge in the construction first described, the rippled upper edge thus provided being adapted to be received in the groove 16 of the shell cases 10 in the same manner as the flanged upper edges of the wall 36 are received and as indicated in Fig. 5. The remaining parts of the structure shown in Figs. 8 and 9 being identical to those previously described are indicated by the same numerals and no further description of the same is required.

It is not essential in the broader aspects of the invention that the flanges along the upper margins of the walls 26 and 36 of the constructions above described be continuous from one end of the charger to the other. Instead, and if desired, these flanges may extend over the length of the arcuate seat portions 28 and 38 only, as indicated in Fig. 10. This construction is perhaps somewhat easier to form in a stamping or drawing operation than the construction first described, but obviously lacks the full strength of the construction first described. Ordinarily, however, it will be found amply strong for the purposes required.

Formal changes may be made in the specific embodiments of the invention described without departing from the spirit or substance of the broad invention, the scope of which is commensurate with the appended claim.

What is claimed is:

45 A shell clip comprising a strip of metal having an arcuate recess in one edge for receiving a shell, the metal along the recess being pressed out laterally and alternately towards opposite sides of the strip so as to provide in effect, a wider edge 50 face for engagement with the shell.
